UNITED STATES PATENT OFFICE

123,896

DESIGN FOR A HOUSING FOR THRESHING AND SEPARATING MECHANISM OF A HARVESTER-THRESHER

Charles J. Scranton, La Porte, Ind., assignor to
Allis-Chalmers Manufacturing Company, Mil-
waukee, Wis., a corporation of Delaware

Application April 22, 1940, Serial No. 91,862

Term of patent 14 years

To all whom it may concern:

Be it known that Charles J. Scranton, a citizen of the United States, residing at La Porte, in the county of La Porte and State of Indiana, has invented a new, original, and ornamental Design for a Housing for Threshing and Separating Mechanism of a Harvester-Thresher, of which the following is a specification, reference being had to the accompanying drawing, forming part thereof.

In the accompanying drawing:

Fig. 1 is a side elevational view of a housing for threshing and separating mechanism of a harvester-thresher, showing my new design;

Fig. 2 is a vertical cross-sectional view taken on the line II—II of Fig. 1;

Fig. 3 is an elevational view showing the side of the housing opposite to that shown in Fig. 1; Fig. 4 is a rear perspective view; and Fig. 5 is a fragmentary front perspective view. I claim:

The ornamental design for a housing for threshing and separating mechanism of a harvester-thresher, as shown.

CHARLES J. SCRANTON.
